CLAIM

The ornamental design for a license plate frame, as shown and described.

DESCRIPTION

FIG. 1 is a perspective front view showing our new design for a license plate frame, with an ornament attached on a top rung of the frame.

FIG. 2 is a perspective front view showing a second embodiment of our design for a license plate frame, with an ornament attached on a bottom rung of the frame.

FIG. 3 is a top view of the license plate frame shown in FIG. 1.

FIG. 4 is a front view of the license plate frame shown in FIG. 1.

FIG. 5 is a right side view of the license plate frame shown in FIG. 1, the left side view being the mirror image thereof.

FIG. 6 is a bottom view of the license plate frame shown in FIG. 1.

FIG. 7 is a back view of the license plate frame shown in FIG. 1.

FIG. 8 is a front view showing a third embodiment of our design for a license plate frame, with an ornament attached in a higher position on the top rung than shown in FIG. 1.

FIG. 9 is a front view showing a fourth embodiment of our design for a license plate frame, with an ornament attached in a lower position on the top rung than shown in FIG. 1.

FIG. 10 is a top view of our design shown in FIG. 2.

FIG. 11 is a front view of our design shown in FIG. 2.

FIG. 12 is a right side view of our design shown in FIG. 2, the left side view being the mirror image thereof.

FIG. 13 is a bottom view of our design shown in FIG. 2.

FIG. 14 is a back view of our design shown in FIG. 2.

FIG. 15 is a front view of a fifth embodiment of our design for a license plate frame, with an ornament attached in a higher position on the bottom rung than shown in FIG. 2 and FIG. 11; and,

FIG. 16 is a front view of a sixth embodiment of our design for a license plate frame, with an ornament attached in a lower position on the bottom rung than shown in FIG. 2 and FIG. 11.
